US0D1017795S

(12) **United States Design Patent** (10) Patent No.: **US D1,017,795 S**
(45) Date of Patent: ** Mar. 12, 2024

(54) **FRAME OF A NASAL MASK**

(71) Applicant: **Fisher & Paykel Healthcare Limited**,
Auckland (NZ)

(72) Inventors: **Callum Ross Gordon**, Auckland (NZ);
Ryan Anthony Graham, Auckland (NZ);
Bruno Sintive, Auckland (NZ);
Mark Andrew Thompson, Auckland (NZ);
Amit Galgali, Auckland (NZ);
Vicky Dan Gao, Auckland (NZ);
Cameron Robert Willis, Auckland (NZ);
Jake Baker Hocking, Auckland (NZ);
Priyanka Ferdinand Pereira,
Auckland (NZ)

(73) Assignee: **Fisher & Paykel Healthcare Limited**,
Auckland (NZ)

(**) Term: **15 Years**

(21) Appl. No.: **29/867,253**

(22) Filed: **Oct. 17, 2022**

Related U.S. Application Data

(62) Division of application No. 29/695,955, filed on Jun. 24, 2019, now Pat. No. Des. 970,720, which is a division of application No. 29/618,347, filed on Sep. 20, 2017, now Pat. No. Des. 855,793.

(57) **CLAIM**

The ornamental design for a frame of a nasal mask, as shown and described.

DESCRIPTION

FIG. 1 is a top, front and side perspective view of a frame of a nasal mask embodying our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines in the drawings illustrate portions of the frame for a nasal mask and form no part of the claimed design.

1 Claim, 7 Drawing Sheets
